US00D721115S

(12) **United States Design Patent**
Park

(10) **Patent No.:** **US D721,115 S**
(45) **Date of Patent:** **** Jan. 13, 2015**

(54) **MONITORING CAMERA**

(71) Applicant: **Samsung Techwin Co., Ltd.**, Changwon (KR)

(72) Inventor: **Ho-Jin Park**, Changwon (KR)

(73) Assignee: **Samsung Techwin Co., Ltd.**, Changwon (KR)

(**) Term: **14 Years**

(21) Appl. No.: **29/459,110**

(22) Filed: **Jun. 26, 2013**

(30) **Foreign Application Priority Data**

Apr. 9, 2013 (KR) 30-2013-0018244

(51) **LOC (10) Cl.** **16-01**

(52) **U.S. Cl.**

USPC **D16/203**

(57) **CLAIM**

The ornamental design for a monitoring camera, as shown and described.

DESCRIPTION

FIG. 1 is a perspective view of a monitoring camera showing my new design;

FIG. 2 is a front elevational view of the monitoring camera; FIG. 3 is a rear elevational view of the monitoring camera; FIG. 4 is a left side elevational view of the monitoring camera; FIG. 5 is a right side elevational view of the monitoring camera;

FIG. 6 is a top plan view of the monitoring camera; and,

FIG. 7 is a bottom plan view of the monitoring camera.

The broken line portions are shown to illustrate environment only and form no part of the claimed design.

1 Claim, 5 Drawing Sheets
